FEEDING DEVICE

Ronald Sydney Buckman and Ray Edwin Neidig,
Calgary, Alberta, Canada, assignors to The
Consolidated Mining and Smelting Company
of Canada, Limited, Montreal, Quebec, Can-
ada, a company of Canada

Application November 9, 1934, Serial No. 752,278

2 Claims. (Cl. 221—120)

This invention relates to improvements in feeding devices by means of which substances of a granular nature such as seeds, fertilizers and the like may be uniformly applied to the soil in predetermined quantities, and has for its object the construction of a device whereby a positive control may be at all times exercised over the quantity of the substance so applied, which means may be easily varied to increase or decrease the rate 10 of feeding as desired.

A further object of the invention is to construct a device in which substances of a different nature may be individually or collectively applied to the soil in predetermined quantities.

15 To carry out the objects of our invention, the device consists of a receptacle such as a hopper provided with a plurality of outlet orifices or ports in one side thereof, a baffle hinged to the inner surface of the same side directly above the orifices and angularly disposed thereto which effectively prevents the free flow of material from the upper portion of the hopper through the orifices, a rotatable shaft or rotor provided with 20 projections rotating in the hopper directly in front of and parallel to the orifices and below the baffle in such a manner that the rotation of the rotor causes a predetermined quantity of material to flow through each of the orifices and thence through suitable spouts or tubes to the soil and effectively prevents any flow of material from 25 the hopper when the rotation of the rotor ceases. The rotation of said rotor also by means of the projections on its periphery passing beneath the said hinged baffle causes the lower edge of this 30 to oscillate sufficiently to keep the material in the box above the baffle always moving downwards toward the rotor. As the rate of flow of material through the orifices depends directly on the speed of rotation of the rotor we have provided means 35 by which the speed of the rotor may be increased or decreased independently of the speed of the carriage on which the device is mounted.

We have found the above mentioned improvements result in a lower construction cost, fewer 45 moving parts thus minimizing the danger of break-downs with the resulting loss of time and repair costs, and at the same time effecting a more uniform application of material to the soil than has heretofore been possible to realize.

50 For a complete understanding of our invention reference is to be had to the following description and accompanying drawings in which:—

Fig. 1 is a rear elevation of a seed drill with 55 this invention attached thereto and acting as a

fertilizer feeding attachment, to distribute fertilizer to the soil with the planting of the seed.

Fig. 2 is an end elevation of a seed drill showing the position of the invention when used as a fertilizer feeding attachment in relation to a seed 5 drill.

Fig. 3 is an end elevation of this invention when used as a fertilizer attachment showing the feeding device on a larger scale than in Fig. 2.

Fig. 4 is an enlarged end sectional view; and 10

Fig. 5 is an end view of a double integral unit constructed in accordance with this invention.

Like characters of reference refer to like parts throughout the specifications and drawings.

As the mechanical construction and operation 15 of all ordinary types of seeding machines are well known to manufacturers and users of agricultural implements, and as our invention relates only to the receptacle and the device for applying the material to the soil, it will only be necessary in the following description to refer to such 20 parts of the seeding machine as are co-ordinated or co-operate with our present invention.

The material feeding device illustrated in the drawings consists of a material box 1 similar to 25 the grain box 2 of the seed drill, and is provided with outlet orifices or ports 5 in one side thereof. A baffle 3 is hinged to the inner surface of the same side directly over the orifices extending downwardly at an angle thereto the full length 30 of the box, and with its lower edge resting on a rotatable shaft or rotor 4 provided with projections, mounted within the box directly underneath the baffle and extending the full length in front of the ports 5. The baffle 3 directs the flow of 35 material from the upper portion of the box to the front of the rotor, the rotation of which pushes the granular substance towards and out of the ports 5 into tubes or spouts 20 which convey it to the soil, and at the same time, the rotation of said rotor beneath said baffle causes 40 the baffle to oscillate to and fro and ensure a continuous flow of material in the box above the baffle to the rotor.

In the construction illustrated, the mechanism 45 for effecting the rotation of the rotor 4 comprises a plate, 21, which is secured to one end of the fertilizer box, 1, and upon which is mounted the gear train and sprockets. One end of a counter-shaft, 9, is journaled in a bearing formed in the 50 plate, 21, at or near the lower extremity thereof, the other end of the counter shaft being supported by a hanger, 24, which is attached to and extends downwardly from the bottom of the box, 1. Mounted on the countershaft 9, between the 55

plate 21 and the hanger 24 is a driven sprocket 8 and on the projection of the counter shaft 9 beyond the plate 21 is mounted a driving sprocket 10. Journalled in the upper part of the plate 21 5 is a shaft 23 upon which is mounted a driven sprocket 12 and a driving spur gear 13 which is driven by the sprocket 12, the spur gear 13 meshing with and driving a spur gear 14 which is mounted on the rotor 4. A driving connection is obtained between the sprocket 10 and the sprocket 12 by means of a transmission chain 11. A split sprocket 6 is fitted to any convenient place on the grain shaft of the seed drill and the 10 rotary motion of the grain shaft is transmitted 15 through the chain 7 to the sprocket 8 mounted on the counter shaft 9.

The invention when constructed as an attachment to a seed drill is removably and adjustably secured to the grain box 2 by means of brackets 20 15 and 17 secured to the seed box and by means of the arms 16 and 18 and 19 secured to the box 1 and extending therefrom to be connected by means of bolts or in any other convenient manner to the brackets. By means of the vertical slot in the bracket 15 and the horizontal slots 25 in the arms 16 and 18 and 19 the attachment may be connected to any type of known seed drill.

As the only material from the box applied to 30 the soil is the predetermined amount pushed through the outlet orifices by the rotation of the rotor, and as the amount required varies for different classes of soil, it has been found necessary to vary the rate of rotation of the rotor in order 35 to obtain a heavier or lighter application. This may be easily accomplished by changing the sprockets 8, 10 and 12, or the gears 13 and 14, or any combination thereof, and replacing them with sprockets or gears of different ratio. The 40 chain 11 is passed over the curved surface of the plate 22 which, being pivotally secured to the plate 21, is adjustable to keep the chain taut regardless of the diameter of the sprockets 10 and 12.

45 While the above described feeding device is particularly applicable to the distribution of chemical fertilizers, it is likewise particularly advantageous for use in the distribution of seed, in that it is of simpler construction than the 50 ordinary seed drill and will distribute such small seed as flax without the necessity of auxiliary appliances, and in that grain seed treated with copper carbonate may be handled more successfully than has heretofore been possible due to 55 the fact that the bearings found in the ordinary type of drill have been eliminated.

Furthermore, when it is desired to distribute to 60 the soil more than one type of material requiring separate distribution to the soil, a double 65 integral unit of the device described may be used advantageously as shown in Figure 5 of the drawings where the device consists of box 1 and box 1a, both of which are provided with outlet orifices or ports 5 and 5a respectively in one side thereof. Baffles 3 and 3a are hinged to the inner surface of the same sides respectively directly above 70 the orifices extending downwardly at an angle thereto the full length of the boxes. Rotatable shafts or rotors 4 and 4a mounted for rotary 75

movement extend the full length of the boxes under the baffles preferably directly in front of the ports 5, 5a. The baffles 3 and 3a direct the free flow of materials from the upper portion of the boxes to the front of the rotors, the rotation of which moves the materials forward to a position where they are pushed out of the ports into tubes or runs, 20, which convey them to the soil, and at the same time the rotary motion of rotors 4 and 4a impart an oscillating motion to 10 the baffles 3 and 3a to and fro so that the material above the baffles in the boxes 1 and 2 is fed downwards in an even stream to the rotors 4 and 4a.

The means by which the rotation of the rotor 15 is effected and the speed of the rotation increased or decreased to effect a heavier or lighter application of any or all the materials so conveyed to the soil is similar to that hereinbefore described.

It will be clearly understood, of course, that 20 the mechanical means for imparting the rotary motion to the rotor is only a preferred construction, and other combination of gears and other means of increasing the rate of rotation of the 25 rotor may be embodied in the device without departing from the scope of the invention.

Having thus fully described our invention 30 what we claim as new and desire to secure by Letters Patent is:

1. A feeding device for applying granular substances to the soil which comprises a receptacle 35 having a plurality of outlet ports in the side thereof, a rotor polyangular in cross section, mounted for rotary movement in said receptacle parallel to and in front of said ports, the rotation 40 of the rotor causing a predetermined quantity of said substance to flow through each of said outlet ports, means for rotating said rotor, a baffle hingedly secured to an inner wall of said receptacle and angularly disposed for directing the flow of the substance toward the bottom of the receptacle in front of said rotor, the free 45 end of said baffle resting on the rotor in such a manner that the rotation of the rotor oscillates the baffle thereby ensuring a continuous flow of the substance in the compartment above the baffle to the rotor.

2. A feeding device for applying granular substances to the soil which comprises a receptacle 50 having a plurality of outlet ports in the side thereof, a rotor polyangular in cross section, mounted for rotary movement in said receptacle parallel to and in front of said ports, the rotation 55 of the rotor causing a predetermined quantity of said substance to flow through each of said outlet ports, means for rotating said rotor, a baffle hingedly secured to an inner wall of said receptacle and angularly disposed for directing the flow of the substance toward the bottom 60 of the receptacle in front of said rotor, the free end of said baffle resting on the rotor in such a manner that the rotation of the rotor oscillates the baffle thereby ensuring a continuous flow of the substance in the compartment above 65 the baffle to the rotor and means for varying the speed of rotation of the rotor.

RONALD SYDNEY BUCKMAN.
